COMBINED DISPENSING COVER AND HANDLE

Walter Schlessel, Lawrence, N.Y., assignor to Gessler Products Corporation, Jamaica, N.Y., a corporation of New York

Filed Sept. 2, 1965, Ser. No. 86,803

Term of patent 14 years

(Cl. D44—21)

FIG. 1 is a side elevational view of a combined dispensing cover and handle showing my new design, with a bottle or the like shown in broken lines for illustrative purposes only.

FIG. 2 is a rear elevational view of the liquid dispenser cover and handle.

FIG. 3 is a top plan thereof, and

FIG. 4 is a front elevational view thereof.

I claim:

The ornamental design for a combined dispensing cover and handle, as shown and described.
